UNITED STATES PATENT OFFICE.

JOSEPH D. MORLEY, OF NEW YORK, N. Y., ASSIGNOR TO SCOTT & WILLIAMS, INCORPORATED, OF BOSTON, MASSACHUSETTS, A CORPORATION OF NEW JERSEY.

TENSION AND TAKE-UP DEVICE FOR KNITTING-MACHINES.

1,186,219.

Specification of Letters Patent.

Patented June 6, 1916.

Application filed February 18, 1916. Serial No. 79,079.

To all whom it may concern:

Be it known that I, JOSEPH D. MORLEY, a citizen of the United States, residing in New York city, New York, have invented 5 certain Improvements in Tension and Take-Up Devices for Knitting-Machines, of which the following is a specification.

The object of my invention is to provide a yielding tension and take-up device for knitted webs, an object which I attain by 10 subjecting the web to the action of beaters disposed transversely to the wales of the web and moving in the direction of delivery of such web, at a higher rate of speed than such delivery.

In the accompanying drawing Figure 1 represents a transverse section of sufficient 15 of a knitting machine to illustrate the application of my yielding tension and take-up device thereto; Fig. 2 is a top view of said device, showing the frame members of the machine in horizontal section on the line α — α , Fig. 1, and Fig. 3 is a face view of a certain retainer plate sometimes used in connection with said tension and take-up device.

In the drawing, I have illustrated my invention as applied to a knitting machine of that type in which the needle cylinder 1 is 20 the stationary member and the cam cylinder 2 is the movable member, but the invention may also be used in connection with a machine in which these conditions are reversed.

As shown in the drawing, the tension and 25 take-up device comprises two circularly arranged series of beaters 3 and 4 disposed transversely to the wales of the web and traveling in the direction of said wales, one series of beaters rotating in one direction 30 and the other series rotating in the opposite direction, and said beaters being so disposed that their paths of travel intersect, a convenient way of effecting this arrangement of the beaters being to cause those of one 35 set to project in one direction from a disk 5 carried by a shaft 5^a and those of the other set to project in the opposite direction from a disk 6 carried by a shaft 6^a, and to cause these shafts to rotate in opposite directions by providing them with intermeshing gear wheels 7, as shown in Fig. 2, either of the shafts acting as a driving shaft and being provided with a pulley 8 or other device to which power is applied.

50 The web is inserted between the beaters 2

and 3 at the point where their paths of travel intersect, whereby the web is first struck on one side by a beater of one set and then on the opposite side by a beater of the other set, as shown in Fig. 1, and so on, by 55 the successive beaters of each set.

The rate of travel of the beaters is in excess of the forward movement of the web, but the latter is held yieldingly between the beaters, which slide over the surface of the 60 web in the direction of movement of the latter, the web being carried forwardly by the frictional hold of the beaters thereupon and being therefore subjected to a yielding tension which will cause it to move forwardly in accordance with its rate of production, and will insure the proper amount 65 of tension at all times upon the course of stitches which is engaged by the needles.

When the machine is one of that type in 70 which movement is imparted to the needle cylinder, the tension and take-up device will have like movement imparted to it and the driving mechanism for the beaters will be modified accordingly, as will be readily 75 understood.

Although I prefer, in all cases, to use two sets of beaters disposed on opposite sides of the web, and having intersecting paths of travel, my invention might, in its broader 80 aspect, be embodied in a device having a set of beaters on but one side of the web, the opposite side having any form of support which would not interfere with the travel 85 of the beaters over the face of the web in the direction of the wales thereof, and although I have shown my invention as applied to a yielding tension and take-up device for knitting machines, it is not limited 90 thereto, but is adapted as well for other uses, as, for instance, in the treatment of knitted webs according to the invention constituting the subject of a separate application Ser. No. 79,080 filed by me of even 95 date herewith.

It may be advisable to subject the web, at a point either above or below the tension and take-up mechanism, or at both points, to such restraint as will prevent movement of the web except in a forward direction. The means which I prefer for this purpose are plates 9 disposed on opposite sides of the web, and having forwardly bent inner edges toothed as shown in Fig. 3, such plates permitting free forward movement of the web 100

110

between them but serving to grip the web and prevent any movement of the same in a reverse direction.

I claim:

5. 1. The combination, in a yielding take-up and tension device for knitted webs, of a series of beaters disposed transversely to the wales of the web, and means for imparting forward movement to said beaters in the direction of said wales and at a higher rate of speed than the forward movement of the web.

2. In a yielding take-up and tension device for knitted webs, the combination of 15 two sets of beaters one on one side of the web and the other on the opposite side of the same, the beaters of one set alternating with those of the other set, and both sets of beaters being disposed transversely to 20 the wales of the web, and means for moving said beaters forwardly in the direction of said wales and at a higher rate of speed than the forward movement of the web.

3. In a yielding take-up and tension device for knitted webs, the combination of 25 two sets of beaters one on one side of the web and the other on the opposite side of

the same, said beaters being disposed transversely to the wales of the web, those of one set alternating with those of the other set, 30 and said sets of beaters having intersecting paths of movement, and means for imparting forward movement to said beaters in the direction of the wales of the web and at a higher rate of speed than the forward movement of said web.

4. The combination, in a yielding take-up and tension device for knitted webs, of a series of beaters disposed transversely to the wales of the web, means for imparting forward movement to said beaters in the direction of said wales and at a higher rate of speed than the forward movement of the web, and means independent of said beaters for preventing backward movement of the 45 web.

In testimony whereof, I have signed my name to this specification, in the presence of two subscribing witnesses.

JOSEPH D. MORLEY.

Witnesses:
